UNITED STATES PATENT OFFICE.

ROBERT L. LYONS, OF WALTHAM, MASSACHUSETTS, ASSIGNOR TO FREDERICK OSANN COMPANY, OF NEW YORK, N. Y., A CORPORATION OF NEW YORK.

SEWING-MACHINE.

1,238,794.

Specification of Letters Patent.

Patented Sept. 4, 1917.

Application filed April 8, 1912. Serial No. 689,220.

To all whom it may concern:

Be it known that I, ROBERT L. LYONS, of Waltham, in the county of Middlesex and State of Massachusetts, have invented certain new and useful Improvements in Sewing-Machines, of which the following is a specification, reference being had to the accompanying drawings, forming part thereof.

This invention has reference to improvements in single thread sewing machines and particularly to that class of single thread sewing machines adapted to form groups of securing or sewing stitches and one or more knotting loops so called.

One object of this invention is to so construct a single thread sewing machine for forming groups of stitches and one or more knotting loops, so called, that said loops may be drawn tight close to the group of 20 stitches and that the thread may be cut close to such tightened loops.

Another object of the invention is to so construct a single thread button sewing machine adapted to form a group of stitches and one or more knotting loops, that the feeding movement of the thread may be stopped, the knotting loops be drawn tight, and the thread strained and cut close to the group of stitches and between the button 30 and the fabric.

Other objects of the invention will appear from the following description.

The invention consists in such peculiar features of construction and combination of parts as shall hereinafter be more fully described and pointed out in the claims.

Figure 1. represents a side elevation, partly in section, of portions of the improved sewing machine.

Fig. 2. represents a sectional plan view of parts thereof taken on line 2—2 Fig. 1.

Fig. 3. represents an end view of portions of the same, partly on section.

Fig. 4. represents a diagrammatical view illustrating approximately the relation of the thread cutter to the knot and to the work and its sustaining means at the completion of the sewing operation after the chain stitches are drawn tight.

Fig. 5. represents a detail view of the thread moving plate.

Similar numbers of reference designate corresponding parts throughout.

As shown in the drawings 10 indicates 55 the base of the machine having the head 11

and the comparatively narrow extension 12 having the throat plate 13 furnished with the throat 14 and the seat or cavity 15 adjacent said throat 14. At one side of said extension 12 is adjustably mounted the support 16 of the guide plate 17 which latter extends over the top of such extension 12 and carries the slidable shank 18 of the cutter blade 19 the hook cutting edge of which extends toward the seat or cavity 15 so that said cutting edge may be carried across, above, the throat 14 when its shank 18 is moved longitudinally. On said extension 12 are the arms 20 and 21 in which is journaled the shaft 22 furnished with lever arm 23, the retracting spring 24 and the collar 25 in a perforation of which is slidably engaged the pin 26 having its upper bent end pivotally engaged in a perforation in the member 18' of said cutter shank 18.

By such construction the support 16 of plate 17 may be adjusted vertically and, in such adjustment pin 26 will slide in the perforation of the collar 25 and thereby follow the vertical adjustment of the cutter shank 18. When shaft 22 is rocked in its bearings pin 26 will actuate said cutter shank 18 to draw the cutting blade 19 transversely above throat 14.

Rotatably mounted in the base 10 is the looper drive shaft 27 having the pinion 28 and the worm 29 which engages the worm gear 30 of the cam 31 rotatably mounted and having the cam groove 32 planned to effect, during rotation of cam 31, a series of vibrations of the follower 33, engaged in said groove, and then to permit the partial rotation of the cam without effecting a relative movement of said follower, whereby the operation of said follower comprises a series of vibrations representing a series of stitches and a dwell representing a chain forming period.

The follower 33 is mounted on the shaft 34 which is journaled in a vertical bearing 100 of the post 35 mounted on said base 10. At its upper end shaft 34 has the grooved arm 36 in the groove of which is mounted the slide member 37 of the clamping device 38, whereby the end of the two part connecting 105 rod 39, pivotally connected with said clamping device 38, may be adjusted along said arm 36 to vary the throw of said rod, while the forward end of said rod 39 is pivotally engaged with the post 40 which has the 110

clamp 41 and is adjustably secured in the base of the standard 42 of the slide member 43 which is slidably mounted on the extension 12 of the base 10, and has the fingers 5 as 44 extending through an opening in said extension 12 and engaged between the collars 45 and 46 of the looper shaft 47 which is slidable and rotatable in bearings of the base 10 and is rotatable by the engagement of 10 pinion 45' of its collar 45 with the pinion 28 of shaft 27 while the collar 46 of the looper shaft has the flange 50 which is engaged in a groove of the thread moving plate 51 having the needle passage 52 and slidably 15 mounted in the base 10.

The head 11 has the lever 53 which is vibrated in any usual manner to effect the vibration of the needle bar 54 which is connected with said lever 53 by the link 55 pivotally connected with said lever and with the member 56 of said needle bar which latter is slidable in the sleeve 57 of the rod 58 and the latter is secured in the clamp 41 of the rod 40.

25 It will thus be seen that during the rotation of cam 31 its cam groove 32 will actuate follower 33 to effect the lateral vibration, through the connections therewith, of slide 43, the looper shaft 47 and looper 48, plate 51 and the needle bar 54 with its needle N in unison while at the same time the needle bar and its needle and the looper will be operated to form stitches. When, however, the dwell 32' in said cam groove 32 travels by 35 said follower 33 no lateral vibratory movement of the needle and the looper will be effected but the stitch forming operation of the needle and the looper will be continued.

The lifter rod 59 is vertically slidable in 40 guides of the head 11 and is pressed downward by the spring 60 acting against the clamp 61 adjustable on said rod 59 which latter at its lower end has the laterally extending presser foot or plate 62 having the fingers 63 and 64 forming the means for engaging the upper edge of a button B, positioned as shown in the drawings, while the lower edge of said button is seated or engaged in the cavity 15 formed in the throat 50 plate 13 adjacent the throat 14. On said rod 59 is adjustably secured the sleeve 65 having at its lower end the flange 66 which supports the swinging arm 67 of a fabric sustaining device which comprises the depending member 68 and the fabric sustaining plate 69 having, preferably, the clearance opening 70 so that when this plate 69 is swung toward a button under operation the edges of the clearance 70 may support the 55 fabric close to the button without obstructing the passage of the needle. Preferably the sleeve 65 is furnished with the spring 71 mounted between the collars 73 and 74 of said sleeve 65 and having the end 72, Fig. 1, 60 which engages the arm 67 and acts to swing

said arm and its member 68 and fabric sustaining plate 69 toward the path of the needle.

By reference to Fig. 3 it will seem that by the release of screw 75 the sleeve 65 may 70 be adjusted along rod 59 to adjust the plate 69 relative to arm 62 which defines the height of the upper edge of the button B when positioned as shown in the drawings. Such adjustment of the plate 69 is for the 75 purpose of adjusting the height of the material or fabric M relative to the center of the button or to its shank b. The manner of mounting plate 69, so that its free end having the clearance 70 may be swung away 80 from the position shown in Fig. 2, in the direction indicated by the arrow, is for the purpose of clearing the way for the placing of the button B beneath the fingers 63 and 64 of arm 62 with the lower edge of the button seated in the seat or cavity 15 of the throat plate 13. In such placing of the button B the plate 69 is first swung outward and then rod 59 with its arm 62 is moved sufficiently upward to permit of the insertion of button B beneath the said fingers 63 and 64.

85 The upward movement of rod 59 is accomplished by the finger 76 of shaft 77 which finger engages with the adjustable 90 clamp 61 of said rod 59. Shaft 77 is journaled in bearings at the side of the head 11 and has the arms 78 and 79 the thread puller arms 80 and 81 and the lifter cam 82. Arm 78 is pivotally engaged by the rod 83 100 which is slidable in a guide of the base 10 and has the plate 84 connected by the chain 85 with any well known actuating mechanism used in sewing machines for raising the presser foot. Arm 79 is connected by 105 chain 86 with the lever arm 23 of shaft 22.

On the head 11 is mounted the thread tension 87, a thread clamp having the member 88 and the arm or clamping member 89, pivotally mounted on the post 90, and the 110 thread guides 91 and 92. This thread clamping member 89 is actuated to the closing position to clamp the thread against the member 88 by the rod 93 which is slidable in guides of the head 11 and has the pin 94 115 bearing on the cam 82.

By slightly raising the presser foot 62 and swinging outward the fabric sustaining plate 69 in the direction indicated by the arrow in Fig. 2 a button B can readily be 120 placed in the vertical position shown in Figs. 1, 3 and 4 with its lower edge engaged or seated in the cavity 15 of the throat plate 13 and with its shank b extending transversely of the throat 14 whereby the perforation in said shank b is adapted to receive the needle N in one or more of the stitch forming movements of said needle. The presser foot 62 is now released, and in its downward movement its members 63 and 130

64 engage the upper edge of said button B and said members 63 and 64 with the cavity 15 of throat plate 13 thus form complementary button holding means.

5 Sleeve 65 is now adjusted along rod 59 and secured in the adjusted position which is relative to the center of the button shank b, so that the material or fabric m folded upon itself and placed on said plate 69 will 10 be located approximately as shown in Figs. 1 and 4 of the drawings.

After the adjustment of said fabric sustaining plate 69 the supporting member 16 of the guide plate 17 is adjusted with reference to the shank b of button B or with reference to the fabric or material m on the sustaining plate 69. The reason for so adjusting the guide plate 18 with reference to the shank b of the button B is to determine 20 the lateral path of movement of the cutter 19 and said guide 18 preferably is moved vertically to a point where it will guide the cutter quite close to button shank b. The thread cutter is not operated until after the 25 completion of a group of sewing stitches and the completion or approximate completion of one or more tying stitches, so called, at which time the thread extends as a loop from the group of tying stitches or knot 30 around the looper and then upward through the work to the needle, and said loop is usually drawn somewhat tight. The path of the cutter 19 is such that its hook end enters said loop of thread while said loop is 35 retained on the looper and cuts that arm of said thread loop which extends from the group of tying stitches to the looper so that the length of thread that extends from the needle, after such cutting, is of a length to 40 extend from said needle downward, around the looper, and upward to the point at which said thread has been cut, so that quite a long portion of thread extends from the needle.

45 The machine is now started and is operated for the usual length of time to effect, through the stitch forming devices, the completion of a group of stitches. In such operation the cam 31 is caused to make a complete rotation whereby the follower 33 is 50 caused to vibrate by the shape of cam groove 32 until said cam rotates to a point where the dwell 32' of said groove holds said follower 33 from vibration. The vibration of the follower 33 is transmitted through shaft 55 34, arm 36 and rod 39 to slide 43 and to the post 40 and rod 58 to sleeve 57 whereby during the rotation of the looper 48 and the reciprocation of the needle bar 54 these parts 60 and the plate 51 are caused to vibrate with respect to the presser foot 62 and the fabric sustaining member 69 so that, in its successive downward movements the needle N passes alternately through the perforation 65 or opening in the button shank b and

through the fabric or material m. At the completion of said group of stitches, when the follower 33 is in the cam dwell 32', the operation of the needle and the looper are continued for one or more, preferably three, 70 loop delivery movements of the needle whereby a chain, so called, is formed between the looper and the stitches which secure the button to the fabric and the thread extends from said chain around the looper 75 back through one loop of said chain and through the fabric or through the perforation in the button shank to the needle and thence through the guides 92 and 91 and between the members 88 and 89 of the thread 80 clamp and, ultimately, to and through the tension device 87 which is set to so resist the feeding movement of the thread that said chain stitches are drawn approximately tight close to the group of stitches which 85 secure the button B to the fabric.

The purpose of the plate 51, in the operation above described, is to prevent the movement of the looper from dragging the loop of thread, extending from said work to the 90 looper, to a point at which the needle cannot enter said loop.

After such completion of the chain stitches rod 83 is actuated to rotate shaft 77 and to effect the lifting of lifter rod 59 95 which of course carries with it the presser foot 62 and the fabric sustaining member or plate 69 whereby the fabric m and the button B sewn thereto are moved upward, that is away from the looper 48. Primarily the 100 rotation of shaft 77 and its cam 82 effects the lifting of rod 93 and the closing movement thereby on the thread clamp member 89 which clamps the thread against its co-operating member 88 to prevent the movement of the thread toward the looper 48. After such clamping of the thread the thread puller 81 engages the thread and draws the same laterally whereby a supply is drawn 105 through the tension 87 to facilitate the starting of another sewing operation. Approximately at this time the thread puller 80 acts to draw laterally on the thread at a point between the thread clamp and the needle to take up the slack thread while the continued movement of the fabric sustaining plate 69, with the work thereon, away from the looper so strains the thread that the arms of the thread loop extending from the knot to the looper are stretched tight, approximately as 110 shown in Fig. 4 of the drawings, whereby, that arm of the thread engaged by the cutter 19 is in a particularly good condition, taut, to be severed thereby, and as such severed arm of the loop is preferably that on which 115 the knots are formed the other arm of the loop extends to and through the needle eye, and is drawn through the work when such work is removed from the machine.

120 By this mechanism the sewing thread is 130

knotted and such thread is cut between the button and the fabric to which it is sewn.

It is not my intention to limit my invention to the specific construction herein shown 5 as I am aware that the same may be modified without departing from the spirit of my invention.

Having thus described my invention I claim as new and desire to secure by Letters 10 Patent.

1. A single thread sewing machine comprising a needle and a looper, complementary button holding means, and means for cutting a thread at a point intermediate said 15 button holding means.

2. A single thread sewing machine comprising a needle and a looper, complementary button holding means, and a thread cutter movably mounted to cut a thread at a point 20 intermediate said button holding means.

3. A single thread sewing machine comprising a needle and a looper, complementary button holding means, means for sustaining fabric above one of said button holding 25 means, and a thread cutter adapted to engage the thread to be cut below the fabric sustaining means.

4. A sewing machine comprising means for holding a button, means for sustaining 30 fabric laterally from said button and above one edge of the button, means for forming a group of securing stitches through said button and fabric and forming knotting loops in the thread, means for drawing said loops 35 tight between the fabric and the button, and means for cutting said knotted thread.

5. A sewing machine comprising stitch forming means, complementary means for holding a button in a vertical position, a 40 thread cutter, and a support for said thread cutter adjustably mounted to adjust said thread cutter relative to the diametrical center of said button.

6. A sewing machine comprising stitch 45 forming means, complementary means for holding a button in a vertical position, a fabric sustaining device adjustable with reference to such holding means, and a cutter extending between said fabric sustaining 50 device and one of said holding means.

7. A sewing machine comprising means for forming a group of stitches and a series 55 of chain loops, means for restraining the movement of the thread toward the work, means for tightening said loops, button holding means, fabric sustaining means, a thread cutter and means for operating said thread restraining means, said loop tighteners and said thread cutter approximately 60 simultaneously.

8. A sewing machine comprising stitch forming means including a needle and a looper, a thread cutter movably mounted and having a path of movement across the 65 path of the needle, means for sustaining a

shank button with its shank extending across said needle path, means for sustaining fabric against said button shank, and means for moving upward said fabric sustaining means and for operating said cutter approximately 70 simultaneously.

9. A sewing machine comprising vibratory stitch forming means, complementary button holding and fabric supporting devices of which the fabric supporting device is adjustable relative to said button holding means, and a thread cutter adjustably mounted and located below the fabric supporting device. 75

10. A sewing machine comprising vibratory stitch forming means including a needle, a looper and a thread moving means located between the looper and the needle, button supporting means, fabric supporting means, and a thread cutter located between 80 said thread moving means and said fabric support.

11. A sewing machine comprising stitch forming means, a throat plate, a presser foot forming with said throat plate complementary 90 button holding means, a fabric support, and cutter located above said throat plate, substantially as described.

12. A sewing machine comprising stitch forming means, a throat plate, a presser 95 foot forming with said throat plate complementary button holding means, a fabric support adjustable with respect to said presser foot, a cutter slidably mounted between said throat plate and said fabric support, and means for operating said cutter, substantially as described. 100

13. A sewing machine comprising a frame having a base, stitch forming means, button supporting means, fabric supporting means movably mounted, a thread clamp, a cutter slidably mounted below said fabric support, and mechanism for operating said thread clamp, said button supporting means, the said fabric support and said cutter approximately 110 simultaneously.

14. A sewing machine comprising a frame having a base, stitch forming means, a cutter support adjustably mounted on said base, a cutter slidably on said support, a rock shaft journaled in bearings of said base and having a collar carrying a slidable pin, said pin pivotally connected with a member of said cutter, substantially as described. 115

15. A single thread sewing machine comprising stitch forming means including knot tying means, a tension, means to draw off a supply of thread through said tension, to start a subsequent stitching operation, and a thread severing mechanism. 120

16. A sewing machine comprising stitch forming means, work carrying means, means for effecting relative movement between the work and said stitch forming means and for arresting said relative movement to effect 130

the formation of a chain stitch, a thread severing device operating on the thread below said chain stitch, and means for drawing off a supply of thread to start a subsequent 5 stitching operation and adapted to move after the operation of said thread severing device to a position to permit the thread to pass to the needle.

17. A single thread sewing machine comprising stitch forming means including knot tying means, a tension, a thread parting member, means operating on the thread between said tension and said stitch forming means to pull said thread through said 10 tension and to hold said thread until said thread has been parted.

18. A sewing machine comprising stitch forming means, means for sustaining two pieces of work in lateral abutment, means for effecting relative movement between 20 said pieces of work and the stitch forming means and for arresting said relative movement to effect the formation of a chain stitch below one of said pieces of work, means for taking up slack thread to draw said chain 25 stitch tight, means for raising one of said pieces of work to strain the thread and means to sever the thread.
